Carl Yurdin, Port Washington, N.Y., assignor to Harman-Kardon, Incorporated, Plainview, N.Y.

Filed Mar. 3, 1971, Ser. No. 120,786

Term of patent 14 years

Int. Cl. D14—01

U.S. Cl. D56—4

The single figure is a left side, top and front perspective view of a phonograph, showing my new design.

The opposite side, not shown, is substantially a mirror image in perspective of the side shown.

The back and bottom, not shown, are essentially plain.

I claim:

The ornamental design for a phonograph, as shown and described.
